UNITED STATES PATENT OFFICE.

GEORGE RICHARDS, OF DOWNSVILLE, WISCONSIN.

LAMP.

1,177,447.

Specification of Letters Patent. Patented Mar. 28, 1916.

Application filed December 15, 1915. Serial No. 66,964.

To all whom it may concern:

Be it known that I, GEORGE RICHARDS, a citizen of the United States, residing at Downsville, in the county of Dunn and 5 State of Wisconsin, have invented certain new and useful Improvements in Lamps, of which the following is a specification.

The invention relates to oil lamps, and more particularly to the class of self-extinguishing lamps.

The primary object of the invention is the provision of an oil lamp of this character, wherein the light therefrom will be automatically extinguished at a predetermined 15 time, thus obviating the necessity of blowing out the flame or turning down the wick for this purpose.

Another object of the invention is the provision of a lamp of this character, wherein 20 the extinguishing device can be readily and easily adjusted so that the flame will be extinguished automatically at any determined time, the device being of novel construction, to assure the positive working 25 thereof.

A further object of the invention is the provision of a lamp of this character, which is extremely simple in construction, thoroughly reliable and efficient in operation, 30 strong, durable, and inexpensive in manufacture.

Other objects will be in part obvious, and in part hereinafter pointed out.

The invention accordingly consists in the 35 features of construction, combination of elements, and arrangement of parts, which will be exemplified in the construction herein-after set forth, and the scope of the application 40 of which indicated in the claims hereunto appended.

In the accompanying drawings: Figure 1, is an elevation of a lamp constructed in accordance with the invention. Fig. 2 is an enlarged fragmentary vertical sectional view. Fig. 3, is a perspective view of the 45 adjustable rod of the extinguishing device. Fig. 4, is a sectional view on the line 4—4 of Fig. 2. Fig. 5, is a sectional view on the line 5—5 of Fig. 4.

Similar reference characters indicate corresponding parts throughout the several views in the drawings.

Referring to the drawings in detail, the lamp comprises a base 10, having a vertical 55 stem 11, supporting a font or reservoir 12, for containing oil, the top of the said font or

reservoir being formed with a central nipple 13, to which is detachably threaded a burner 14, having a central wick tube 15, in which is arranged a wick 16, the latter 60 depending within the font or reservoir 12, as usual. Journaled within the burner 14, is a wick adjusting shaft 17, having the ordinary spur wheel 18, for engagement with the wick 16, for feeding the same through 65 the burner in the ordinary well known manner, for increasing or decreasing the flame when the lamp is lighted. Arranged within the font or reservoir 12, is a buoyant float 19, which is connected with the section 20, of a two part adjustable rod, the other section 21, of which is formed at its upper end with a right angular extension 22, terminating in a sleeve or eye 23, in which is threaded a set screw 24, for adjustably connecting it with a link 25, slidably fitted in a chimney holder 26, mounted upon the burner 14, and this holder supports a burner hood 27, which surrounds the wick tube 15, in the burner, as usual. The upper end of 70 the section 20, of the adjustable rod is formed with an eye 28, which loosely surrounds the section 21, for slidably connecting the same, while the section 21, at the lower end is formed with a resilient latch 75 29, for adjustably locking the sections of the rod together. Cut from the chimney holder 26, on opposite sides of the burner 14, are upstanding bearings 30, in which is journaled a rocking shaft 31, having formed 80 thereon an inverted substantially L shaped flame extinguishing wing 32, which is adapted to swing into and out of the path of the flame from the burner 14, and when in the path of the flame will automatically extinguish the same. One end of the shaft 31, is formed with a crank 33, to which is pivotally connected the link 25, so that on movement of the float 19, the extinguishing wing 85 32, will be operated.

On the outer side of the font or reservoir 12, is a vertically arranged scale 34, having time indicia thereon, indicative of an hour and fractions thereof, so that the float 19, can be set by adjusting the rod 90 supporting the same, for the extinguishing of the flame of the burner at any predetermined time, it being understood of course that the float rides upon the surface of the oil within the font or reservoir and 105 when the latter is consumed up to a given point in the scale the flame is automatically 110

extinguished by the operation of the wing 32, moving into the path of the latter. Mounted on the wick tube 15, at one side thereof is a permanent magnet 35, which 5 has its poles terminating at the end of the burner 14, to attract the wing 32, when automatically shifted for drawing said wing down onto the wick tube 15, for positively extinguishing the flame when the 10 burner is lighted. It will be apparent that when the float is adjusted the flame of the burner will be automatically extinguished at a predetermined time.

From the foregoing it is thought that the 15 construction and manner of operation of the lamp will be clearly understood and therefore a more extended explanation has been omitted.

Pivoted in the holder 26, is a lock 33, 20 which is movable into engagement with the extension 22, to normally hold the extinguishing device inoperative.

What is claimed is:

1. In a lamp, an oil reservoir, a burner 25 having a wick tube, a magnet arranged at one side of the wick tube, a flame extinguisher at the other side of the wick tube and adapted to be attracted by the magnet when moved across the path of said tube, 30 a cranked shaft pivotally mounting the extinguisher on the burner, a float within the reservoir, a link connected with the crank of the shaft and depending without the burner, a rod section fixed to the float and

extended without the reservoir, a rod section 35 adjustably connected with the link and arranged parallel with the first named rod section, eyes on the respective rod sections for slidably connecting the same, and a spring latch bent from the last named rod 40 section and engaged with the first named rod section for adjustably locking the same together.

2. In a lamp, an oil reservoir, a burner having a wick tube, a magnet arranged at 45 one side of the wick tube, a flame-extinguisher at the other side of the wick tube and adapted to be attracted by the magnet when moved across the path of said tube, a cranked shaft pivotally mounting the extinguisher on the burner, a float within the reservoir, a link connected with the crank of the shaft and depending without the burner, a rod section fixed to the float and 50 extended without the reservoir, a rod section 55 adjustably connected with the link and arranged parallel with the first named rod section, eyes on the respective rod sections for slidably connecting the same, a spring latch bent from the last named rod section 60 and engaged with the first named rod section for adjustably connecting the same together, and a locking device on the burner for holding the extinguisher normally inactive.

65 In testimony whereof I affix my signature.

GEORGE RICHARDS.
